UNITED STATES PATENT OFFICE.

MILFORD G. CHANDLER, OF CHICAGO, ILLINOIS, ASSIGNOR TO CHANDLER ENGINE VALVE COMPANY, OF CHICAGO, ILLINOIS, A CORPORATION OF ILLINOIS.

INTERNAL-COMBUSTION ENGINE.

1,219,917.

Specification of Letters Patent. Patented Mar. 20, 1917.

Application filed May 27, 1914. Serial No. 841,262.

To all whom it may concern:

Be it known that I, MILFORD G. CHANDLER, a citizen of the United States, residing at Chicago, in the county of Cook and State of Illinois, have invented a new and useful Improvement in Internal-Combustion Engines, of which the following is a specification.

My invention relates more particularly to internal combustion engines having rotary valve mechanism for controlling the inlet of the fuel to the engine cylinder or cylinders, or the exhaust of the burnt-gases therefrom, or both, and especially to multi-cylinder engines.

My objects, generally, are to provide a novel and simple construction of valve mechanism especially of the spherical type, whereby when used singly, or in multiple and connected together to operate in unison from a common driving means, the valve, or valves, proper will be adapted to shift independently of each other to conform to the surfaces with which they coöperate to form gas-tight joints; which may be readily assembled with the other parts of the engine and readily removed therefrom, and other objects as will be apparent from the following description.

Referring to the accompanying drawings—

Figure 1 is a view in vertical sectional elevation of the upper end of an internal combustion engine of the four-cycle four-cylinder type, equipped with valve-mechanism constructed in accordance with my invention, the section being taken at the line 1 on Fig. 2 and viewed in the direction of the arrow. Fig. 2 is a section taken at the line 2 on Fig. 1 and viewed in the direction of the arrow. Fig. 3 is a broken section taken at the line 3 on Fig. 2 and viewed in the direction of the arrow. Fig. 4 is a broken section taken at the line 4 on Fig. 2 and viewed in the direction of the arrow. Fig. 5 is a face view of one of the disks forming the mechanism for transmitting driving power from the source to the shaft carrying the valves proper. Figs. 6, 7, 8 and 9 are perspective views of the disk of Fig. 5 and the rings forming said transmitting mechanism. Fig. 10 is a section taken at the line 10 on Fig. 2 and viewed in the direction of the arrow, showing the up-

per portion of the engine; and Fig. 11, a plan view of a portion of the engine.

The engine in which I have chosen to illustrate my invention and in connection with which I have more particularly devised my improvements, is of the four-cycle multiple cylinder type, having four cylinders 10, with a crank-shaft-operating piston 10^a for each cylinder, my improved valve-mechanism being shown as controlling the inlet of gas to, and the exhaust of burnt gas from, the cylinders.

Extending across the top of the cylinders is a housing 11 which, at intervals, immediately above each cylinder 10, forms a valve-casing 12 of general spherical internal contour, as represented, these valve-casings opening into the respective cylinders 10 through ports 13, each of which serves as a port for both the intake and exhaust, the wall of each port 13 containing an annular recess 14 which surrounds the port and opens into the valve-casing 12 immediately above it, and contains a packing-member 15 preferably of metal having its inner end of spherical contour for engagement with the spherical valves hereinafter described, the members 15 being backed up by springs 16 for forcing them in close contact with the peripheries of the valves.

The housing 11 is formed with a passage 17 for the fuel to be supplied to the cylinders 10, this passage opening at one end into the adjacent ends of a pair of valve-casings 12, at its other end into the adjacent ends of the other pair of valve-casings, and communicating, intermediate its ends, with a pipe 18 leading from the source of fuel supply (not shown), as, for example, a carburetor. The housing 11 also contains a passage 19 which opens into the adjacent ends of the two intermediate valve-casings 12, and two passages 20 which open respectively into the outer ends of the end valve-casings 12, the passages 19 and 20 communicating with a manifold 21 and serving as passages for conveying the exhaust gases from the cylinders 10.

Each valve-casing 12 contains a valve proper 22 of general spherical contour against which the packing members 15 at their spherical inner ends bear under the action of the springs 16. Each of the valves 22 is hollow with open ends, as shown, and is

formed with a hollow hub 23 and a diagonally-disposed wall, or partition 24, which defines non-communicating chambers 25 and 26 therein, one open to one end of the valve 5 and the other chamber open to the other end of the valve, ports 27 and 28 in the periphery of each valve opening into the chambers 25 and 26, respectively. The chamber 25 with its port 27 forms an intake chamber 10 communicating with the passage 17, and the chamber 26 with its port 28 forms an exhaust-chamber which opens, in the case of the two intermediate valves 22, into the passage 19, and in the case of the end valves 22 open into the passage 20.

15 The valves 22 are mounted on a rotary shaft 29 for simultaneous operation, to cause the intake and exhaust chambers of the valves to register alternately at their ports 27 and 28 with the respective ports 13 of the cylinders 10, in properly timed relation to the movements of the pistons of the engine for permitting introduction of charges into the cylinders, and the escape of exhaust 25 gases therefrom at the proper times in accordance with common practice. The shaft 29 extends through the housing 11 lengthwise of the latter, the housing containing openings 30 and 31 at opposite ends to receive the shaft 29, the opening 30 being closed by a screw-cap 32. The valves 22 are secured to the shaft 29 preferably by splines, in the form of pins 33, which pass through the shaft 29, these pins extending at one end 30 into longitudinal key-ways in the hubs 23 of the valves, whereby the valves rotate when the shaft is turned but may shift longitudinally thereon to adjust themselves to the bearing surfaces they engage on the interior 35 of the valve-casings.

40 To prevent exhaust gases from the cylinders, escaping into the passages for fuel and thus contaminating it, the adjacent ends of each pair of valves 22 are connected at their hubs 23 by sleeves 35, the ends of the hubs 23, for this purpose, being preferably of reduced diameter as illustrated at 36, and the sleeves fitting the hubs sufficiently tightly to prevent any exhaust gases which might find 45 their way into the sleeves 35 from escaping into the fuel passages, but not too tight to prevent the valves 22 from shifting lengthwise relative to each other.

45 The shaft 29 may be driven in properly timed relation to the pistons in the cylinders 10, for the purpose above stated, by any suitable means, but it is preferred that it be driven from the crank-shaft (not shown) of the engine by the mechanism illustrated 50 which provides the desired flexible connection between the shaft 29 and the drive shaft to prevent strain on the shaft from side thrust of the drive-mechanism and permits the shaft and valves to operate under all 55 conditions without undue friction from

binding, a description of the valve-driving mechanism being as follows:

Keyed to an end of the shaft 29, as represented at 37, is a disk 38 provided with a circumferential series of equidistantly spaced 70 openings 38^a, and having a flange 39 on its inner face surrounded by a ring 40 containing openings 40^a arranged as in the case of the openings 38^a, with screws 41 passing through certain of the openings 38^a and 40^a 75 for securing the ring 40 and disk 38 together. The inner side of the ring 40 carries diametrically-opposed lugs 42 which fit into recesses 43 in a ring 44 concentric with the ring 40, the ring 44 having diametrically-80 opposed recesses 45 on the face thereof opposite to that containing the recesses 43, but arranged at 90° to the last referred to recesses, the recesses 45 receiving lugs 46 provided on the end of a worm-gear 47 which is 85 journaled on a flanged bushing 48 encircling a cylindrical extension 49 provided on a head 50 bolted to the end of the housing 11. The shaft 29 passes loosely through the head 50, and the outer end of the opening in the 90 head for the shaft is enlarged, as represented at 51, being screw-threaded, as represented at 52, to receive a bushing 53 which latter, with the shoulder 54 at the base of the enlarged opening 51 co-operates with a packing-ring 55 releasably fitting the shaft 29, by frictional engagement for preventing exhaust gases escaping into the housing 55^a for the above-described transmission mechanism. 95

100 The gear 47 which is driven from a worm 56 on a shaft 57 driven from the crank-shaft of the engine, causes the shaft 29 and the valves 22 thereon to rotate, and the above-described mechanism, between the gear 47 and the shaft 29, thus provides a flexible 105 connection which prevents the binding of the valves.

110 The parts of the housing 11 forming the upper half of each valve-casing 12, are formed in cap-sections 58, which rest upon shoulders 58^a in the housing and are held in place by blocks 59.

115 The key-ways 34 in the valves preferably occupy, in each valve, the same relative position to the ports 27 and 28, so that certain of the valves are interchangeable, and the pins 33 are so arranged about the shaft 29 that when the various pins thereon engage the key-ways of the respective valves, the valves will occupy the proper positions relative to each other on the shaft, so that when they are connected with the driving-mechanism hereinbefore described, they will properly time the inlet of gas to, and the exhaust of burnt gas, from the various cylinders. 120 To assemble the valve mechanism with the other parts of the engine, assuming the driving-mechanism for the shaft 29 to be assembled to the position shown, and the caps 58 having been removed, the valves 22 125 130

are introduced from the top of the engine into the lower portions of the valve-casings 12, and in this operation telescoped with the sleeves 35, and the shaft 29 thereupon inserted through the opening 30 in the housing and successively through the hubs of the valves to the position illustrated in Fig. 1, the key-ways 34 in the hubs of the valve being so disposed as to cause the valves, when the pins 33 on the shaft lie within the key-ways, to assume the correct angular position relative to each other for producing proper timing of the inlet to and exhaust from the engine cylinders when the shaft 29 is operated. During the assembling of the shaft with the valves as stated the shaft 29 enters the ring 55. The shaft 29 is then turned to such a position as will cause the key-way in the shaft 29 for receiving the key 37 to register with the latter and the shaft then moved to the position illustrated in the drawings, the key 37 being so disposed that upon adjusting this shaft about its axis to cause the key 37 to enter this key-way, the valves 22, each properly positioned relative to each other on the shaft 29 as stated, will occupy such positions relative to the ports 13 and the means for driving this shaft, that the valves will operate in properly timed relation to the pistons in the cylinders.

When occasion requires that the valves 22 be removed from the engine, the operator upon removing the cap 32 pulls the shaft to the right in Figs. 1 and 2 through the housing 11 and the valves, whereupon, the cap-sections 58 having been removed, the valves may be lifted out of the engine.

The relatively large number of holes 38^a and 40^a are provided to permit of the relative adjustment of the disk 38 and ring 40 to insure the proper timing of the shaft 29.

It will be readily understood from the foregoing that upon removal of the shaft 29 and valves 22 the position of the shaft-driving mechanism is not disturbed so that the reassembling of the shaft and valves with the said driving mechanism may be effected without requiring adjustments for properly timing the operation of the shaft 29. It is preferred that the housing 55^a be provided with an internal flange 55^b which will support the disk 38 when the shaft 29 is removed.

In the particular construction illustrated, the engine cylinders are inclosed in a fluid-tight casing 60 which extends upwardly about the housing 11 as indicated in Fig. 1 and forms a jacket for receiving air or water, preferably circulated therethrough as is usual in internal-combustion engines, for cooling the engine, the fluid thus introduced not only cooling the cylinders but also the valve-casings 12 relatively great areas of which are subjected to the fluid. The re-

movable sections 58 of the casings 12 are preferably packed as indicated at 61 between annular upwardly extending flanges 62 thereon and annular flanges 63 on the housing 11 and concentric with, but spaced from, the flanges 62, circular retaining rings 64 fitting between these flanges and against the packing 61 to prevent the cooling-fluid from entering the casings, the rings 64 being held down against the packing by screws 65 screwing into the sections 58 and overlapping the rings 64 at their heads. It will be noted that the provision of the packing 61 as described will permit of the adjustment of the cap-sections 58 toward and away from the cylinders without impairing the joint between these cap-sections and the housing.

While I have illustrated a particular construction embodying my invention, I do not wish to be understood as intending to limit it thereto, as the same may be variously modified and altered without departing from the spirit of my invention.

What I claim as new and desire to secure by Letters Patent is—

1. In an internal combustion engine, the combination with its cylinder, of a valve-casing having a spherical inner surface opening into said cylinder through a single port, a spherical valve in said casing for controlling said port containing non-communicating chambers opening through the opposite ends, respectively, of the valve and each containing a port in the periphery of the valve for alternate registration with said cylinder-port when the valve is actuated, a shaft, means splining the valve to said shaft permitting longitudinal movement of said valve on said shaft, and means for rotating said shaft.

2. In an internal-combustion-engine, the combination with its cylinder, of a valve-casing communicating with said cylinder and having alined bearings, said casing being formed of sections one of which is removable relative to said bearings and is interposed between the latter, the joint between said sections extending lengthwise of the casing, inlet and exhaust pipes communicating with said casing, a rotatable valve in said casing for alternately opening the inlet and exhaust pipes to said cylinder, a shaft releasably connected with said valve and removable, when disconnected from said valve, by drawing it lengthwise through said bearings, and means for actuating said shaft.

3. In a multiple-cylinder internal-combustion engine, the combination of a plurality of alined valve-casings communicating respectively with the cylinders of the engine and open at their ends, said valve-casings having alined bearings and being formed of sections certain of which are removable relative to said bearings and are interposed be-

- between the latter, inlet and exhaust pipes communicating with the interior of said casings, rotatable valves in said casings for alternately opening the inlet and exhaust pipes to said cylinders, a shaft releasably connected with said valves and removable, when disconnected from said valves, by sliding it lengthwise through the said bearings, and means for actuating said shaft.
4. In a multiple-cylinder internal-combustion engine, the combination of a plurality of alined ported valve-casings for the cylinders having alined bearings, said casings being formed of sections certain of which are removable relative to said bearings and are interposed between the latter, the joints between said sections extending lengthwise of the casings, rotatable valves in said casings for controlling the ports therein, a shaft extending through said casings and carrying said valves, said shaft being withdrawable from said valves and casings through the ends of said casings by withdrawing it lengthwise through said bearings, and means for actuating said shaft.
5. In a multiple-cylinder internal-combustion engine, the combination of a plurality of alined ported valve-casings for the cylinders having alined bearings, said casings being formed of sections certain of which are removable relative to said bearings and are interposed between the latter, the joints between said sections extending lengthwise of the casings, rotatable valves in said casings for controlling the ports therein, a shaft extending through said casings and on which said valves are splined, said shaft being withdrawable from said valves and casings through the ends of said casings by withdrawing it lengthwise through said bearings, and means for actuating said shaft.
6. In a multiple-cylinder internal combustion engine, the combination of a plurality of alined ported valve-casings for the cylinders, a rotatable valve in each casing for controlling the ports in the latter, a shaft extending through said casings, said shaft carrying splines arranged in different angular positions about the shaft, said valves containing keyways disposed in each valve in the same position relative to its ports, and means for actuating said shaft.
7. In an internal combustion engine, the combination with alined ported valve-casings, rotatable valves in said casings controlling the ports therein, inlet and exhaust pipes communicating with ports of said casings, means for actuating said valves, and means extending from one valve to the other for preventing exhaust gases from escaping into said inlet pipe.
8. In an internal combustion engine, the combination with alined ported valve-casings, rotatable valves in said casings controlling the ports therein, inlet and exhaust pipes communicating with ports of said casings, means for actuating said valves, and a sleeve extending from one valve to the other for preventing exhaust gases from escaping into said inlet pipe.
9. In a multiple-cylinder internal combustion engine, the combination with alined valve-casings communicating with the cylinders of the engine, inlet and exhaust pipes communicating with the interiors of said valve-casings, rotatable valves in said casings controlling the ports therein, means for actuating said valves, and means extending from one valve to another for preventing exhaust gases from escaping into said inlet pipe.
10. In a multiple-cylinder internal combustion engine, the combination with alined valve-casings communicating with the cylinders of the engine and open at their ends, inlet and exhaust pipes, the inlet to said valve-casings being at opposite ends of the latter and the exhaust from the other ends thereof, rotatable valves in said casings controlling the inlet to, and the exhaust from, the cylinders, means for actuating said valves, and means extending from one valve to the other for preventing the escape of exhaust gases into the inlet passages.
11. In a multiple-cylinder internal combustion engine, the combination with alined valve-casings communicating with the cylinders of the engine and open at their ends, an inlet pipe communicating with the inner open ends of the casings, an exhaust pipe communicating with the outer open ends of the casings, rotatable valves in said casings controlling the inlet to, and the exhaust from, the cylinders, means for actuating said valves, and means extending from one valve to the other for preventing the escape of exhaust gases into the inlet passages.
12. In a multiple-cylinder internal combustion engine, the combination with alined valve-casings communicating with the cylinders of the engine and open at their ends, inlet and exhaust pipes, the inlet to said valve-casings being at opposite ends of the latter and the exhaust from the other ends thereof, rotatable valves in said casings each containing non-communicating chambers, openings through opposite ends of the valves and having ports adapted to register alternately with the openings from the valve-casings into the cylinders, means for actuating said valves, and means extending from one valve to the other for preventing the escape of exhaust gases into the inlet passages.
13. In a multiple-cylinder internal combustion engine, the combination with alined valve-casings communicating with the cylinders of the engine and open at their ends, inlet and exhaust pipes, the inlet to said valve-casings being at opposite ends of the latter and the exhaust from the other ends

thereof, rotatable valves in said casings controlling the inlet to, and the exhaust from, the cylinders, a shaft extending through said valves and on which the latter are splined, 5 means for actuating said shaft, and means surrounding said shaft and extending from one valve to the other for preventing the escape of exhaust gases into the inlet passages.

14. In a multiple-cylinder internal-combustion engine, the combination with aligned valve-casings communicating with the cylinders of the engine and open at their ends, an inlet passage open to the inner ends of said valve-casings, an exhaust passage open 10 to the outer ends of said valve-casings, rotatable valves in said casings containing non-communicating chambers, the chambers in each valve opening, respectively, through the opposite ends of said valve and containing 15 ports adapted to be moved alternately into communication with the interior of the respective cylinders, a shaft extending through said valves and on which the latter are splined, means for actuating said shaft, and 20 sleeves surrounding said shaft and extending from one valve to the other and forming joints, so positioned as to be subjected to charges passing to the cylinders, for preventing leakage of exhaust gases into the 25 fuel supply.

15. In a multiple-cylinder internal-combustion engine, the combination with aligned valve-casings communicating with the cylinders of the engine and open at their ends, 30 inlet and exhaust passages, the inlet to said valve-casings being at opposite ends of the latter and the exhaust, from the other ends thereof, rotatable valves in said casings provided with non-communicating chambers 35 opening through the opposite ends of the valves and provided with ports adapted, when the valves are rotated, to be moved alternately into communication with the interior of the cylinders, said valves being 40 formed with hub-portions, a shaft extending through said hubs and on which said valves are splined, means for actuating said 45

shaft, and a sleeve surrounding said shaft and the inner opposing ends of said hubs and forming joints, so positioned as to be 50 subjected to charges passing to the cylinders, for preventing leakage of exhaust gases into the fuel supply.

16. In an internal-combustion engine, the combination with its cylinder and piston, of a housing forming a section of a ported valve-casing for the cylinder and having an opening at the side thereof farthest from the piston and extending beyond the portion thereof which forms a section of said valve-casing, the internal surface of said valve-casing being of spherical form and provided with a shoulder, a removable member fitting into said opening in the housing and resting against said shoulder and forming with 60 said housing the valve-casing, a rotatable valve in said casing, and means for directing a cooling-fluid against said member.

17. In an internal combustion engine, the combination with its cylinder, of a housing forming a section of a ported valve-casing for the cylinder and extending beyond the portion thereof which forms a section of said valve-casing, a removable member fitting into said housing and forming therewith the valve-casing, packing interposed between said removable member and housing, a rotatable valve in said casing, and means for directing a cooling fluid against 70 75 said section.

18. In an internal combustion engine, the combination with its cylinder, of a housing forming a section of a ported valve-casing for the cylinder having its internal surface of spherical form and provided with a shoulder, a removable member fitting into said housing and against said shoulder and forming with said housing the valve-casing, a rotatable valve in said casing, and means for directing a cooling fluid against said member.
